UNITED STATES PATENT OFFICE.

ALBERT D. SMITH, OF ROCKFORD, ILLINOIS.

SEWING-MACHINE.

1,261,170.

Specification of Letters Patent.

Patented Apr. 2, 1918.

Application filed December 27, 1915. Serial No. 68,789

To all whom it may concern:

Be it known that I, ALBERT D. SMITH, a citizen of the United States, residing at Rockford, in the county of Winnebago and 5 State of Illinois, have invented certain new and useful Improvements in Sewing-Machines, of which the following is a specification.

This invention relates in general to the 10 art of sewing machines and has more particular reference to that class characterized by the employment of a rotary hook or looper and a rotary take-up for sewing a lock stitch, and has further reference to 15 two-spool sewing machines, that is, those in which both the upper and lower thread is supplied from ordinary spools.

One of the primary objects of my invention 20 is to provide a commercially practical sewing machine containing various improvements designed to obviate numerous undesirable features in sewing machines now in common use. I have also aimed to provide a sewing machine so improved in construction 25 and operation as to be exceedingly light running, easily operated and controlled, and capable of being manufactured at a comparatively low cost. In materializing these general improvements, my invention 30 contains various specific objects, as follows:

One object of my invention is to provide a 35 practical two-spool thread supply. This obviates the necessity of winding bobbins and, in conjunction with a rotary looper, effects smooth and light running. So far as I am aware, the means devised prior to my 40 invention for providing such a thread supply have been complicated in construction and expensive to manufacture, and further, are objectionable as a commercial product in that they did not permit the use of a sufficient range of differently sized spools ordinarily used in sewing machines. I have, 45 therefore, provided a novel spool receptacle for holding the lower spool, so constructed that any of a large range of differently sized spools may be easily and conveniently inserted into and removed from the receptacle. Furthermore, the spool receptacle is so de- 50 signed that it may be produced at a low cost and itself forms means for guiding and controlling the loop of the upper thread formed by the looper.

Another object is to arrange the spool 55 receptacle in co-operation with a rotary hook or looper by mounting in an improved man-

ner the receptacle upon a stationary support that is mounted in a race-way in the rotary hook. More specifically, the spool receptacle of a general U-shape cross-sectionally 60 is pivotally mounted on a longitudinal axis at its lower end substantially in the plane of the race-way and inclined obliquely so that the open side of the receptacle is disposed uppermost and toward the front of 65 the machine. By this construction, the receptacle is centrally disposed within the rotary hook, the downwardly converging outer sides of the receptacle forming guide surfaces for the loop which is passed around the receptacle. The receptacle may be swung on its pivot from set working position to one wherein a spool may be easily inserted into and removed from the receptacle through an opening in the work plate of 70 the machine.

Other objects and advantages will be apparent as the invention becomes better understood by reference to the following description when considered in connection with 80 the accompanying drawings, wherein I have illustrated one working embodiment of the invention, and wherein—

Figure 1 is a front elevation of a sewing machine containing my improvements; 85

Fig. 2 is a cross-sectional view through the sewing machine showing an end elevation of my improvements;

Fig. 3 is a sectional view taken on the line 3—3 of Fig. 2; 90

Figs. 4, 5 and 6 are detail views of the spool-case support;

Fig. 7 is a perspective of the spool-case or receptacle, a portion of the thread tension device thereon being broken away; 95

Fig. 8 is a perspective view of the auxiliary loop controller; and

Fig. 9 is a perspective view of the rotary hook.

In the drawings I have illustrated only 100 so much of a sewing machine as is necessary for an understanding of my improvements. Referring particularly to Figs. 1 and 2, it will be observed that I have shown a conventional type of work plate 21, head 22, 105 and goose neck 23 in which is mounted a shaft 25 journaled in bearings 26 beneath the work plate 21, which shaft 25 is driven from the shaft 24 through the intermediary of a vertical shaft 27 connected at its upper 110 end by one to one bevel gears 28 with the shaft 24 and at its lower end with three to

one bevel gears 29 with the shaft 25. By this arrangement of gearing the shaft 25 is rotated three times to every rotation of the shaft 24. The shaft 24 drives the needle-bar and rotary take-up and the shaft 25 the rotary hook or looper as is common in sewing machines of this general character. Legs 31 support the work plate 21 at such a distance above a surface on which the machine head is set that the rotary hook will not be interfered with, it being understood that in use the sewing machine head is mounted on a suitable stand.

The construction of the needle-bar 32, presser-bar 37 and its operating lever 39, feed bar 44, rotary take-up 52, and in fact, all of the mechanism shown above the work plate 21 is not claimed in this application, hence a detail description herein of such mechanism is deemed unnecessary. My present improvements, relating in general to the rotary hook structure and the control of the lower and upper threads below the work plate 21 will now be described.

25 The lower thread, taken from a spool contained in a suitable receptacle is in a stationary bobbin. The spool receptacle 66 is mounted on a stationary support 67 in turn mounted in a race-way in a rotary hook 68, these reference characters being applied to generally designate their respective parts. The upper thread is taken from the needle by the point of the hook and passed in a loop about the stationary spool receptacle in a manner well known in the art, with the exception that the loop is controlled in a novel way by my improved mechanism. This mechanism is designed especially for controlling a comparatively 40 large loop, which is required to be passed around the large spool case. Fig. 9 clearly shows the construction of the rotary hook. It comprises an annular casing 69 formed with a hook point 71, a depressed heel 72, 45 a race-way 73, and spider arms 74 securing the annular casing to the hub 75, which is fixedly connected to the shaft 25. The spool case support, best shown in Figs. 4 and 5, is so designed that it may be pressed out 50 of sheet metal. The said support seats in the race-way, and a retaining plate 76 screwed to the annular casing 69 and forming the outer side wall of the race-way holds the support against displacement 55 therefrom. The support 67 has the usual cutaway 77 and loop spreader 78. The central portion of the support 67 is pressed out to form flanges 79 and 81 intermediate and upon which the spool receptacle is pivotally mounted. These flanges 79 and 81 constitute stationary thread guides for guiding and controlling the loop, and it will be noted that a curved continuation of the flange or thread guide 81 is provided in the form of a 60 flange 82 which in the present instance is

constructed by pressing or raising a peripheral or marginal portion of the blank from which the support 67 is formed, to substantially right angles to the plane of said blank, in the manner clearly shown in Figs. 4 and 5. The lower ends of the flanges 79 and 81 are rounded as at 83 to shed the loop as it passes and the upper ends of the flanges 79 and 82 are shaped to provide fingers or thread guides 84 and 85 which converge upwardly and are adapted to prevent the loop from crossing the path of the hook point. The finger 85 serves, by its engagement in the recess 86 of the stationary bar 87, as the means for holding the support 67 against rotation, while the finger 84 terminates just short of the bar 87. In the present instance, I have shown a flat spring 88 attached to the underside of the finger 85 and arranged to abut against a wall of the recess 86 so as to resiliently hold the support 67 against rotation. The spring 88 is not, however, necessary to successful operation of the sewing machine, as will appear hereinafter.

90 The spool receptacle 66, preferably pressed out of sheet metal, has downwardly converging side walls 89 and 91 joined by end walls 92 and 93, so as to provide a receptacle of general V or U shape in cross-section. The 95 receptacle 66 interposed between the flanges 79 and 81 is pivotally mounted thereon by means of a pivot pin 94 passing through the narrow ends of the end walls 92 and 93 of the receptacle. It will be noted, viewing Fig. 2, that the pivot axis of the receptacle 66 is so inclined that the open side of the receptacle is disposed uppermost and toward the front of the machine, and also that the said pivot axis lies substantially in the plane 100 of the race-way so that the receptacle is centrally disposed relatively to the loop which is passed thereover. It will be further noted that the downwardly converging outer sides 89 and 91 of the receptacle form 110 means for guiding the loop about the spool. A spring catch holds the receptacle in working position and permits the receptacle to be released against a given spring pressure from said central position and swung outwardly on its pivot to permit access to the interior of the receptacle. This spring latch, in the present instance, is formed by a portion 95 of the end wall 93 being shaped to yieldingly engage the edge 96 of the support 120 67 to hold the receptacle against rocking on its pivot. It will be manifest that upon swinging the receptacle 66 outwardly to a position limited by the front wall 89 of the receptacle abutting against the adjacent edge 125 of the support 67, a spool may be passed downwardly through the opening 97 in the work plate into the receptacle. Viewing Fig. 3, it will be apparent that due to the general V-shape of the receptacle, spools of 130

various diameters may be employed. A spool inserted into the receptacle 66 rests on the downwardly converging interior walls thereof and may turn freely thereon, and thus any of a large variety of differently sized spools may be placed in the receptacle and will automatically assume a proper working position therein, since this position is determined merely by the spool resting on interior walls of the receptacle. The thread from the lower spool is passed downwardly through a V-shaped slot 98 in the said wall 89 and thence upwardly in said slot and over the portion 99, Fig. 7, of the receptacle wall. A flat spring 101 bears yieldingly on the portion 99 and thus forms a spring tension for the lower thread. The tension of the spring 101 may be adjusted by turning the screw 102 which, as will be seen in Fig. 3, connects the raised portion of the spring to the spool receptacle. The thread-engaging end of the spring 101 has an end portion 103 turning over the edge of the wall 89 forming a stop for limiting outward movement of the spring and also forming a guide for the lower thread, since this passes upwardly over the guide 103 and through the recess 86 of the bar 87 to the needle-way.

An auxiliary loop guide or controller of peculiar shape, best shown in Figs. 2 and 8, and designated in general by reference character 104, is mounted on a stationary support of the sewing machine separate from the spool receptacle support and parts appurtenant thereto and is adapted to cooperate with the thread-guiding means 82, 84 and 85 described above in controlling the loop after it has been cast off from the point of the hook. This thread controller in the form of an angular piece of sheet metal is connected by means of a screw 105 and stud 106 to a lug 107 depending from the underside of the work plate 21 and extends diagonally to the front and left of the rotary hook viewing Fig. 1. Thus the said controller extends angularly to the hook in a horizontal plane and thence inclines upwardly, as shown in Fig. 2, into the space above the spool receptacle and terminates in close proximity to the base of the thread-guiding arm 85 and relatively close to the support 67, as indicated in Figs. 2 and 6. It will be noted, viewing Figs. 6 and 8, that the inner edge of the controller 104 is shaped to provide a thread-guiding edge 108 that is adapted to draw the loop beneath the flange 82 and substantially to the support 67 for a purpose which appears hereinafter.

The operation of the rotary take up (which is merely spoken of generally in this application for purpose of illustration) in conjunction with the rotary hook to produce lock stitching will now be described. Referring especially to Fig. 2 and assuming that a piece of cloth is held beneath the

presser foot, after the machine has been threaded, it is ready for sewing. A spool of thread is so placed in the spool receptacle 66 that the thread is taken from the underside of the spool. After inserting the spool and swinging the receptacle back to set position, the loose end of the thread is entered in the slot 98 and guided therealong by a downward and then upward movement until the thread is engaged by the spring tension 101, the end of the thread being extended from the said tension a sufficient length for the loop to take the said end when being drawn up. The upper thread from the spool 59 is passed over guide 61 on the back 80 of the head 22, thence downwardly over the corner 109 of the face plate 49 and between the tension disks 63, the thread being entered therebetween at the rear side thereof and passed in a counterclockwise direction, viewing Fig. 2, around the disk. The thread is then passed through the rotary take-up 52 in a clockwise direction over the pin 53 thereof, and thence downwardly beneath the hooked end 111 of the thread guide 64 and beneath the guide 65 from the right hand side thereof. This completes the guide means for the upper thread, which thread is now passed through the eye of the needle.

With the needle at its highest point, as shown in Fig. 2, the take-up pin 53 has drawn nearly its full amount of slack thread, so that upon the down stroke of the needle there is but a small amount of thread drawn up. The hook point 71 passes the needle way once before the needle reaches its lowest point, and when the needle is drawn up to form a small loop at its eye, the hook point having in the meantime made another revolution, takes the loop from the needle. The loop after being spread by the spreader 78 is drawn down by the hook point or looper and passed around the spool receptacle. When the hook has reached its lowermost point, it has drawn down the full amount of slack from the take-up, the pin 53 of which is at its lowest point. The length of loop required to be passed around the spool receptacle is, so far as I am aware, greater than that necessary to be passed around any spool or bobbin case now in use. This is because of the comparatively large size of my improved spool receptacle, which is designed to contain a larger spool than any spool container that I have knowledge of. Consequently a large range of differently sized spools ordinarily used in sewing may be employed by the use of my improvements.

The loop in being passed about the spool receptacle is held slightly taut against the sides 91 and 92 thereof. These downwardly converging sides constitute very effective means for gradually spreading the loop and controlling the same until it has passed

around the receptacle. The loop is cast off from the hook just after leaving the receptacle. The hook point and the take-up pin are approximately at the points C and C', respectively, (Fig. 2) at this stage of the sewing. The loop as it is drawn up by the take-up gathers the loose end of the lower thread and draws it up to the cloth as is well understood. However, because of the comparatively large loop and the relative timing of the take-up and rotary hook, the take-up does not draw the loop up fast enough to keep it away from the point of the hook, which during this period will pass through its upper cycle of rotation.

In order to prevent the loop from crossing the path of the needle or from twisting or in any way being caught in the mechanism, I have provided means for positively controlling the loop while it is being drawn up. The front and upper portion of the loop is guided along the outer edge of the flange 79 and finger 84 and thus held out of the path of the needle. The rear portion of the loop, after the cast-off, passes through the cutaway 77 and is guided along the flange 82 and finger 85. Just after the cast-off and as the loop is being drawn up in engagement with the guides 77, 84, 82 and 85, the end of the loop engages the inner edge of the auxiliary controller 104 and is drawn inwardly by its edge 108 so as to hold the loop slightly taut. It will be manifest that, the end of the loop will follow along the edge 108 which takes up the slack of the loop and draws the end of the loop beneath the front edges of the flanges 79 and 82. By the time the loop reaches the end of the edge 108, the hook point has passed the needle-way and the short remaining loop still held against the fingers 84 and 85, can in no way foul the hook point or become twisted. As the loop is finally drawn up, it passes between the spring 88 and the wall of the recess 86 engaged by the spring, which yields to give passage to the thread so that the support 67 is not moved. However, this spring is not necessary and the finger 85 may itself bear against the bar 87, in which case the support 67 will be slightly moved as the end of the loop is drawn up. This completes the stitch, the several movable parts of the sewing machine being then in the position shown in Fig. 2 in which position the cycle of operation was commenced.

In operating the machine the driving shaft 24 turns in a clockwise direction, viewing Fig. 2, and it will be apparent that if the shaft is turned in the opposite direction, the machine will not sew since the hook point will not take the thread from the needle; and it will be further apparent that if the said drive shaft is turned in a reverse direction but a slight distance when

the upper thread loop is engaged by the hook point, the latter will be drawn from the loop and will possibly not reengage it when the drive shaft is again turned in the right direction. It will also be noted that due to the three to one gearing, a slight reverse movement of the shaft 24 will cause a reverse movement of the rotary hook great enough to withdraw its point from the loop. To prevent this occurrence, I have provided means for automatically preventing even the slightest movement of the rotary hook in a reverse direction. This means consists of a friction clutch in the form of a gravity ball 145 (Fig. 2) coöperating between the peripheral face 146 of the annular case 69 of the rotary hook and an arcuate face 147 of a depending bracket 148 secured to the under side of the work plate 21. The face 147 nonconcentric with the peripheral face 146 forms an inclined abutment, between the face of which and the peripheral face 146, the ball 145 will bind at the instant the rotary hook commences to turn in the reverse direction, that is, in a clockwise direction, viewing Fig. 2. It will be seen that by utilizing the rotary-hook casing as one of the elements of the friction device, I have provided a very simple and effective means for preventing movement of the rotary hook in a reverse direction.

While in the foregoing, I have illustrated and described one practical, working embodiment containing my improvements, it should be understood that various changes in the construction and arrangement of parts may be resorted to without departing from the spirit and scope of the invention as expressed in the appended claims, wherein—

I claim:

1. In a rotary-hook sewing machine, the combination with a rotary hook, of a spool receptacle of general U-shape cross-sectionally providing a spool opening between its spaced sides, and means pivotally supporting said receptacle within the rotary hook in such manner that the receptacle may be swung on its pivot from a set position for sewing to a position wherein a spool may be passed into and out of the receptacle through its spool opening.

2. In a rotary-hook sewing machine, the combination with a rotary hook, of a spool receptacle having an open side where-through to pass a spool into the receptacle and being pivotally mounted within the rotary hook and movable on its pivot from a set position for sewing wherein the open side of the receptacle is disposed uppermost to a position wherein a spool may be passed into and out of the receptacle through its open side.

3. In a rotary-hook sewing machine, the combination with a rotary hook, of a spool

105

100

110

115

120

125

130

receptacle disposed within the rotary hook, comprising a body having in cross section downwardly converging walls and an open side at the divergent ends of said walls and 5 being pivotally mounted at its narrow side on a substantially stationary axis extending longitudinally of the body and so located relatively to the rotary hook that the said body is disposed within the hook with its open 10 side uppermost, whereby the spool receptacle may be swung on its pivot between working and spool-receiving positions and whereby also spools of various sizes may be placed in the receptacle and rest and turn on the 15 said converging walls thereof.

4. In a rotary-hook sewing machine, the combination with a rotary hook and a stationary spool-case support mounted on a race-way in the rotary hook, of a spool case 20 pivotally mounted on said support on an axis disposed substantially in the plane of the race-way and provided with an open upper side for the reception of a spool and side walls converging downwardly from 25 said open side so that a spool may rest and turn on said walls, and means for holding the spool case in a set working position wherein its open side is disposed uppermost and for permitting the said spool case to 30 swing laterally to a position wherein a spool may be passed into and out of said case through the open side thereof.

5. In a sewing machine, the combination with a rotary hook having a race-way there- 35 in, of a stationary spool case support mounted in said race-way and formed of a flat piece of metal with a central portion pressed out to provide oppositely disposed thread guides adapted for guiding the loop drawn 40 out by said hook and with a marginal portion bent to form a thread guide continuation of one of said thread guides.

6. In a rotary hook sewing machine, the combination of a rotary hook having an annular raceway, a spool support mounted on 45 said raceway, a spool receptacle mounted on said support within the raceway and having an open upper side and downwardly converging walls upon which a spool may 50 rest and be revoluble, said spool receptacle being so constructed that its outer convergent wall may be swung from a position in which a spool is operatively retained to an outer position in which the spool may be 55 freely removed from the receptacle through its open top.

7. In a rotary hook sewing machine, the combination of a rotary hook having an annular raceway, a spool receptacle carried

by the support and shaped to revolvably support a spool within the raceway on an inclined axis extending downwardly and toward one side of the machine and including a pivoted retaining wall at the face of the rotary hook adapted to be swung from a 65 position in which to operatively retain a spool to an outer position in which the spool may be freely removed from the receptacle.

8. In a rotary hook sewing machine, the combination of a rotary hook having an annular raceway, means mounted on the raceway for carrying a spool or the like within the raceway and provided with outstanding thread guides disposed within the raceway and extending about certain sides of a spool 70 for guiding the loop as it is drawn up by the needle, and an auxiliary thread controller in the form of a stationary arm arranged so that its end terminates intermediate said thread guides a substantial distance inwardly of the thread guiding edges thereof and adjacent to the needle way so as to guide the end of the loop inwardly a substantial distance with respect to said thread guides to prevent the loop from foul- 75 ing the hook.

9. In a rotary hook sewing machine, the combination of a rotary hook having an annular raceway therein, a stationary spool support mounted on said raceway, a spool 90 receptacle or supporting means mounted on the spool support within the raceway and movable with respect thereto from spool-receiving to working positions, the spool support having outstanding thread guides 95 extending substantially circumferentially about a portion of the spool receptacle for guiding the loop as it is drawn around the same, and a stationary auxiliary thread controller extending from a point beyond the 100 face of the rotary hook intermediate and beyond the said circumferentially arranged thread guides and terminating in proximity to the needle way for drawing the end of the loop over said thread guides and inwardly with respect to their thread guiding edges to prevent the loop from fouling the hook.

10. In a sewing machine, the combination of a rotary hook, a drive shaft, means operative between the drive shaft and rotary hook for revolving the latter at a faster speed than the former, and means for automatically frictionally engaging an annular wall of the rotary hook to immediately prevent rotation thereof in a direction opposite to its working direction of rotation.

ALBERT D. SMITH.
